(57) **CLAIM**

The ornamental design for a combined keychain and digital recorder, as shown and described.

DESCRIPTION

FIG. 1 is a perspective view of a combined keychain and digital recorder according to the present invention.

FIG. 2 is a front view of the combined keychain and digital recorder of FIG. 1.

FIG. 3 is a rear view of the combined keychain and digital recorder of FIG. 1.

FIG. 4 is a right side view of the combined keychain and digital recorder of FIG. 1.

FIG. 5 is a left side view of the combined keychain and digital recorder of FIG. 1.

FIG. 6 is a bottom view of the combined keychain and digital recorder of FIG. 1; and,

FIG. 7 is a top view of the combined keychain and digital recorder of FIG. 1.

The dashed broken lines illustrate portions of the combined keychain and digital recorder that form no part of the claimed design.
